GLASS ANNEALING LEHR

Carroll Cone, near Toledo, Ohio, assignor to Surface Combustion Corporation, Toledo, Ohio, a corporation of New York

Application July 29, 1936, Serial No. 93,248

8 Claims. (Cl. 49—47)

This invention has for its object to provide a glass annealing lehr which shall embody improvements in means for controlling the distribution of heat in a lehr tunnel of such width as to accommodate two ware conveyors arranged side by side in the tunnel.

In the accompanying drawings wherein the preferred form of the invention is shown:—

Fig. 1 is a side elevation of the improved lehr, the view being on a greatly reduced scale as compared with the other views;

Fig. 2 is a longitudinal vertical section of that portion of the lehr where the heating zone may be said to end and the cooling zone to begin;

Fig. 3 is a fragmentary cross sectional view along line 3—3 of Fig. 2;

Fig. 4 is a longitudinal vertical section of the heating portion of the lehr, not all of the parts, however, being in the same vertical plane;

Fig. 5 is a transverse vertical section through the lehr, the left hand portion being taken closer to the front end of the lehr than the right hand portion, the view as a whole illustrating features of the heating portion of the lehr, and

Fig. 6 is a fragmentary horizontal section of the lehr, the view illustrating certain features of the heating portion of the lehr.

Referring to Fig. 1, it will be seen that the lehr is a relatively long affair, the first or left hand portion thereof being a heating zone and the next succeeding portion being a cooling zone as is customary in continuous glass annealing lehrs.

In accordance with the present invention, the lehr tunnel is sufficiently wide to accommodate two endless belt conveyors 10 arranged side by side in the tunnel. Both of these conveyors are of the open work type, such as a wire mesh belt, to permit the free passage of gases therethrough. The belts are individually supported in any preferred way as on rollers 11 supported by a suitable framework including side irons 12. The lower or return strand 10' of both belts may also extend through the lehr tunnel but for illustrative purposes such strand is shown as extending outside 45 of the tunnel where it is supported in any preferred way as on rollers 11'.

It is a feature of the present invention that the two conveyors are independently driven thus permitting two independently moving rows of 50 glassware to be independently heat treated as conditions demand. The conveyors are independently driven in any preferred way as by individual driving drums 14 at the ware discharge end of the lehr.

Extending across the lehr tunnel some distance

inwardly from the ware intake end thereof is a structure formed to provide two independent front chambers 16 in end to end relation and two independent rear chambers 17 also arranged in end to end relation. The front wall 16' of both chambers 16 is apertured to provide outlets 5 opening into the lehr tunnel and the rear wall 17' of both chambers 17 is apertured to provide outlets opening into flues 24 individual to the chambers 17.

Associated with each front chamber 16 is a pressure burner 18 and associated with each rear chamber 17 is a pressure burner 19. The burners 18 for the front chambers 16 are preferably of somewhat greater capacity than the burners 19 15 for the rear chambers 17 but otherwise all of the burners are of the same type, namely, a type adapted to burn explosive gaseous mixture. As shown in Fig. 5, the preferred type of burner comprises a tubular combustion chamber 20 of refractory material, the mixture being delivered 20 to said chamber by a nozzle 21, the supply pipe for the latter being indicated at 22. Each of the supply pipes 22 for the several burners is provided with a flow controlling means 23 which may be either a hand operated valve or a valve mechanism adapted to be automatically controlled by means responsive to temperature conditions at certain points in the heating zone of the lehr tunnel. As shown in Fig. 6, each of said chambers 16 and 17 preferably decreases in width inwardly 30 away from its burner end to insure uniform outflow of gases throughout the extent of its apertured side wall.

The flues 24 whereinto the gases from the chambers 17 discharge do not extend the full length of the lehr tunnel but only a sufficient distance away from said chambers to provide for proper heat distribution at points remote from such chambers. As viewed in Fig. 1, the flues would terminate at about the point 26. The top-side of each flue 24 comprises metal plates 27 provided with openings 28 arranged in rows crosswise of the flue and each row of openings is controlled by a damper 29 secured to an operating rod 30 which extends outside of the lehr tunnel. As shown in Fig. 4, the damper 29' at the intake end of each flue 24 is so arranged as to cause the gases issuing from the underlying row of outlets 28 to be deflected back over the top of the chamber 17 whereas the other dampers are mounted to deflect the issuing gases in the general direction of the travel of the conveyors 10.

The combustion gases supplied to the several chambers 16 and 17 are augmented and tempered 55

by gases withdrawn from the lehr tunnel by means next to be described. On top of the lehr at a point intermediate the ends of the heating zone thereof is a housing 31 for a fan 32 on a drive shaft 33 coupled to a driving motor 34. The intake end 35 of the housing opens into the tunnel through the roof thereof either at a point midway the width of the roof as is shown or at a plurality of points at either side of the center line of the roof. The discharge end of the housing is indicated at 36 and it opens into a duct 37 which extends across the top of the lehr tunnel and then downwardly at each side thereof as side ducts 38 one of which opens into one set of front and rear chambers 16 and 17 respectively and the other into the other set of similar chambers. It will, therefore, be understood that the gases withdrawn from the lehr tunnel by the fan 32 are delivered some to each of the two front chambers 16 and some to each of the two rear chambers 17.

As shown in Fig. 5, there is positioned in the cross duct 37 crosswise thereof and centrally of the housing outlet 36 a vane 39 which is coupled to a slideable adjusting rod 40. By adjusting the vane toward the right or left as viewed in Fig. 5, the relative volumes of gases delivered to the right and left hand branches 38 of the duct may obviously be controlled as desired. There is also provided in the lower end of each side duct 38 a vane 41 mounted on a turnable rod 42. By varying the angularity of the vane 41 the relative volumes of gases delivered into the adjacent chambers 16 and 17 from the duct 38 may obviously be varied as desired.

It may at times be desirable to add outside air to the tunnel gases entering the fan housing 31 and to this end the housing is provided with a valve controlled opening 43, the valve being shown 40 as a disk 44 adjustably mounted on a fixed rod 45.

The heating zone of the lehr tunnel is followed by a cooling zone which may be considered as beginning where the heating zone ends, namely, at the point 26 as viewed in Fig. 1. From that point 45 on the ware is gradually cooled by introducing controlled volumes of cooling air into the tunnel. The means for introducing the cooling air preferably takes the form of a horizontally extending row of air discharge nozzles 47 along each side 50 of the tunnel, the nozzles at one side being preferably staggered with respect to those at the other side and both rows of nozzles being arranged below the ware conveyor 10. Each nozzle has its own control valve 48 and its supply pipe 49 55 and is positioned to discharge into a throat 50 at the lower end of a vertical duct 51, the upper end of which is in direct communication with the interior of the cooling zone as indicated at 52. The downdraft produced in the various side ducts 60 51 sets up circulation of the gases in the cooling zone as will be readily appreciated. By thus introducing cooling air at a plurality of longitudinally spaced points and causing the air to circulate from the upper to the lower portion of the 65 cooling zone, it will be readily appreciated that the rate of cooling of the ware may be readily controlled within a wide range.

At longitudinally spaced intervals in the roof of the lehr tunnel are vents 53 through which 70 tunnel gases may be expelled to the atmosphere as conditions may demand, it being noted that each vent is provided with a damper 54.

The new and useful results obtained by a lehr embodying the improvements herein shown and 75 described will be readily apparent to those skilled

in the art but may be briefly considered as follows:

Since the two longitudinally extending flues 24 are supplied with heating gases independently of the two front chambers 16, it will be readily appreciated that by regulating the amount of fuel supplied to the burners 18 associated with the said chambers 16, the temperature conditions at the ware intake end of the lehr tunnel may be controlled independently of the temperature conditions resulting from the outflow of heating gases from the flues 24. Moreover, since the burners 18 associated with said chambers are individually regulable, it becomes a relatively simple matter to maintain proper heat balance at the ware intake end of the lehr tunnel in cases where 10 one of the conveyors 10 carries glassware of one weight and the other conveyor carries glassware of a different weight. Furthermore, since the gases withdrawn from the lehr tunnel by the fan 32 may be distributed as desired by adjusting 20 the position of the vanes 39 and 41, it will be readily appreciated that even without disturbing the adjustment of the various burners 18 and 19, it is possible to control the distribution of heating effects both lengthwise and crosswise of the 25 lehr tunnel. The adjustable dampers 29 associated with the flues 24 also materially assist in the obtainment of the desired heat distribution.

As compared to a single conveyor covering the full width of the lehr tunnel, the use of two conveyors permits handling of two classes of ware simultaneously, one of which may be heavy pieces occupying relatively little belt area but requiring a long annealing time and the other of which may consist of thin pieces requiring only a short annealing cycle. It will be obvious that a single conveyor carrying such a composite load would have to be run at low speed in order to give the required time cycle for the heavy ware. The low belt speed would, of course, seriously limit the 40 amount of light ware that could be put through the lehr and, moreover, the long annealing cycle then applied to the light ware would in many cases result in mechanical deformation of the ware. The advantages of utilizing two independently 45 driven conveyors will, therefore, be readily appreciated.

What I claim is:

1. In combination, a lehr tunnel, two conveyors arranged side by side in the tunnel for conveying glassware therethrough, two parallelly arranged flues one below each conveyor and extending lengthwise of the tunnel, means forming two chambers one for each conveyor crosswise thereof adjacent the ware intake end of the tunnel, burners individual to said chambers and to said flues for discharging hot combustion gases thereinto, means for withdrawing gases from the tunnel and for delivering the same to said flues and chambers, means for controlling the amount of withdrawn gas delivered to the respective flues and chambers, and each of said flues and chambers having outlets opening into the tunnel for discharging the gases into the latter.

2. The combination specified in claim 1, characterized by the burners for the said chambers being of greater capacity than the burners for the flues.

3. The combination specified in claim 1, characterized by means individual to the respective flues for controlling the outflow of gases from their said outlets.

4. The combination specified in claim 1, characterized by each flue being substantially as wide 75

as the width of the conveyor below which it is disposed.

5. In combination, a lehr tunnel, two conveyors arranged side by side for conveying glassware therethrough, two parallelly arranged flues one below each conveyor and extending lengthwise of the tunnel for a substantial distance from the ware intake end of the tunnel, means forming two chambers one for each conveyor crosswise 10 thereof between the ware intake end of the tunnel and the respective flues, burners individual to said chambers and to said flues for discharging hot combustion gases therewith, means for withdrawing gases from the upper portion of the 15 tunnel and for delivering the same to the respective chambers and flues, and each of said chambers and flues having outlets opening into the tunnel for discharging gases into the latter.

6. In combination, a lehr tunnel, means for 20 conveying glassware through the tunnel, two flues arranged side by side below said means and extending lengthwise of the tunnel from the ware intake end of the tunnel, means forming two chambers arranged end to end crosswise of the

tunnel adjacent the ware intake end thereof, burners individual to said chambers and to said flues for discharging hot combustion gases therewith, means for withdrawing gases from the upper portion of the tunnel and for delivering the same under pressure to the respective chambers and flues, and each of said flues and chambers having outlets opening into the tunnel for discharging gases into the latter. 5

7. In combination, a lehr tunnel, two independently operable conveyors inside of the tunnel for conveying glassware therethrough, and means including two chambers each extending approximately half way across the tunnel from opposite sides thereof for establishing heating 15 zones through which the conveyors pass.

8. In combination, a lehr tunnel, two independently operable conveyors inside of the tunnel for conveying glassware therethrough, and independently controllable means below each 20 conveyor for discharging heating gases into the tunnel.

CARROLL CONE.
